UNITED STATES PATENT OFFICE

GEORGE P. KINGSBURY, OF HOLLIS, NEW YORK, ASSIGNOR TO MERGENTHALER LINOTYPE COMPANY, A CORPORATION OF NEW YORK

TYPOGRAPHICAL COMPOSING MACHINE

Application filed May 2, 1929. Serial No. 359,759.

This invention relates to typographical composing machines, such as linotype machines of the general organization represented in U. S. Letters Patent to O. Mergenthaler No. 436,532, wherein circulating matrices are stored in a channeled magazine, released therefrom in the order in which their characters are to appear in print, and then assembled in line, the composed line transferred to the face of a mold, the mold filled with molten metal to form a slug or linotype against the matrices, which produce the type characters thereon, and the matrices thereafter returned through distributing mechanism to the magazine from which they started. The release of the matrices from the magazine is ordinarily effected by a series of key-controlled power-operated escapements, each comprising a 10 rocking lever which is actuated in one direction by a spring and in the other direction by a sliding plunger, and a pair of reciprocating pawls which are moved alternately into and out of the magazine by the rocking lever in controlling the release of the matrices one at a time therefrom. The escapement lever, under the influence of its actuating spring, normally holds the front pawl in engagement with the leading matrix, but 20 when the sliding plunger is pushed rearwardly, it rocks said lever against the tension of the spring to its reverse position, withdrawing the front pawl from engagement with the leading matrix, which is thus allowed to escape, and projecting the rear pawl into the path of the next or succeeding matrix of the column to arrest it momentarily. When pressure on the actuating plunger is later relieved, the spring acts immediately to restore the escapement lever to its first or original position, the rear pawl being withdrawn from engagement with said succeeding matrix and the front pawl being moved back into the magazine to intercept and sustain this matrix, which now becomes the leading one. At each operation of the escapement, first one pawl and then the other is abruptly stopped in its upward movement by shoulders formed on the pawls, which shoulders bank against finished surfaces of the escapement supporting frame and thus limit the rocking movements of the escapement lever. Escapement mechanisms of this type, while in general use, are expensive to manufacture and require great care and precision in the mounting and assembling of the various parts. Furthermore, the escapements are quite bulky and take up so much room that they prevent the magazines from being arranged as closely together as 55 60 65 70 75 80 85 90 95

The present invention is directed to a novel form of escapement, which will obviate the foregoing difficulties, and which at the same time will be capable of use in the commercial machines or in connection with the standard magazines without necessitating changes in the other parts. Moreover, the improved escapement is simple, inexpensive to manufacture, and comprises a minimum of parts. The construction of the escapement supporting frame is also equally simple and such that any one of the escapements may be quickly and conveniently removed for repair or replacement without disturbing the others. In the preferred embodiment illustrated, the escapement merely comprises a pair of matrix engaging pawls and a fore-and-aft spring-actuated slide member, which is formed with oppositely disposed cam surfaces adapted to move the pawls alternately into and out of the magazine as the slide is reciprocated. 100

In the accompanying drawings, the invention is shown only in preferred form and by way of example, being designed to suit standard equipment, but obviously many changes and variations may be made therein and in its mode of adaptation which will still be comprised within its spirit. It should be understood, therefore, that the invention is not limited to any specific form or embodiment, except insofar as such limitations are specified in the claims.

Referring to the drawings:

Fig. 1 is a side elevation of a linotype machine equipped with a series of superposed magazines and having the improved escapements applied thereto;

Fig. 2 is an enlarged vertical section 100

through the lower end of a magazine and the escapement supporting frame, showing an escapement in its normal position;

Fig. 3 is a vertical section similar to Fig. 2, showing the position of the escapement reversed;

Fig. 4 is a detail transverse section taken on the line 4—4 of Fig. 2;

Fig. 5 is a bottom plan view of a portion of the escapement supporting frame assembled; and

Fig. 6 is a detail perspective view of an escapement pawl detached.

The matrices X (see Fig. 1) are stored in a series of inclined channeled magazines A, arranged one above the other in closely spaced relation and mounted on separate base frames A¹, which conjointly constitute a shift frame, the latter being movable upwardly and downwardly in the machine to bring one or another of the magazines into operative relation to the fixed assembler throat B. Matrices released from the magazine in use pass into the throat B and thence to the assembler (not shown), wherein they are composed in line preparatory to casting. After casting, the line of matrices is elevated to the distributing mechanism C and the individual matrices restored thereby to their respective magazine channels.

Each magazine is provided with a series of escapements mounted in a separate supporting frame hinged to the corresponding base frame A¹ and detachably connected to the magazine, so that the magazine may be removed at will for interchange without removing the escapements. The operation of the escapements is controlled from the keyboard D through the medium of a series of power-operated reeds D¹ and a corresponding series of pivoted levers D², the levers D² being carried in the fixed machine frame and having their upper ends located in position to engage the escapements of any selected magazine when the latter is brought into operative position.

So far as described, the parts, their construction, and mode of operation, except as hereinafter pointed out, are or may be the same as embodied in the commercial linotype machine.

As before stated, the present invention is devoted to an improved escapement for controlling the release of the matrices one at a time from their magazine. As best shown in Figs. 2 and 3, each escapement consists essentially of a pair of pawls E¹, E², movable alternately into and out of the magazine, and a fore-and-aft reciprocable cam slide E³ for operating the pawls. The escapements of each magazine (there being one for each column of matrices in the magazine channels), are mounted in a common supporting frame F, which is pivotally connected by

means of side arms F¹ to the magazine base frame A¹ (see Fig. 1).

The pawls E¹, E² of an individual escapement are spaced the usual distance apart, but in the present instance they are slidably mounted in the supporting frame F so as to move in planes perpendicular to the plane of the magazine and thus present square banking surfaces to the matrices at all times. At their lower ends, the pawls are guided in notches f formed in the opposite edges of a plate or bar F² secured to the underside of the supporting frame F, and at their upper ends they are similarly guided in notches f¹ formed in the opposing walls of a longitudinal aperture in the frame F, a retaining bar F³ detachably secured to the frame F and which fits snugly between said walls being provided to maintain the pawls properly within their guideways. The plate F³ might, if desired, be made integral with the supporting frame F, but being detachable, it facilitates the assemblage and disassembly of the parts.

The cam slide E³ is disposed transversely across the supporting frame F from front to rear and fits in open recesses e—e (Fig. 6) formed in one side of the pawls E¹, E², the arrangement being such that the slide not only sustains the pawls vertically, but moreover is capable of sliding freely back and forth within said recesses. At the front, the slide E³ is formed with an exposed depending nose portion e⁵, and at the rear with an upstanding or a depending lip or shoulder e⁶, as the case may be. Between its ends, the slide E³ is formed with oppositely disposed offset or cam surfaces e¹—e²—e³—e⁴, adapted, as the slide is reciprocated, to engage the upper and lower walls of the recesses e—e and thus raise and lower the escapement pawls in the manner required. While the resistance offered by the pawls E¹, E² is slight, the walls of the recesses e—e, are rounded off so as to reduce the friction between the parts and ease up their operation.

The cam slides E³ of each series of escapements are mounted in cuts milled in the lower face of the escapement supporting frame proper and are held in place by two retaining plates F⁴, F⁵, common to all of the slides and arranged on opposite sides of the plate F² in flush relation thereto. The plates F², F⁴, F⁵, are all screwed to the supporting frame F (as shown in Fig. 5), so that one or all may be conveniently removed when it is desired to gain access to the enclosed parts for inspection, changing, or repair, etc.

Each slide member E³ is held resiliently in its forward position by a compression spring E⁴ interposed between the rear end of the slide and a fixed back plate F⁶ fastened to the frame F, the springs being confined in the space provided by a recess F⁷ formed in the rear portion of the supporting frame F and

a corresponding recess F^8 formed in the retaining plate F^3 . Due to the close spacing of the escapements, the springs E^4 for adjacent slides (as will be noted from Fig. 4) are arranged at different levels or staggered so that they may act freely without interference with each other. In this connection, it may also be observed (see Figs. 2 and 3) that the rear ends of the slides E^3 and the back plate F^6 are formed with aligned protuberances over which the springs are seated and which serve to prevent their accidental displacement.

In adapting the slides E^3 to such staggered arrangement of the springs E^4 , the lips e^6 of every other slide are preferably arranged to project upwardly from the rear edges thereof, while the lips of the intermediate slides, are arranged to project downwardly therefrom. These lips e^6 however, are intended primarily to limit the forward movement of the cam slides E^3 , and hence they are caused to bank against finished front walls f^2-f^3 of the recesses F^7 , F^8 , respectively, so as to locate the cam surfaces e^2-e^3 of the slides in proper relation to the escapement pawls without unnecessary lost motion. The rearward movement of the slides E^3 is likewise limited by the engagement of the rear edge 30 of their respective nose portions e^5 with the front edge of the plate F^4 so as to locate the cam surfaces e^1-e^4 in proper relation to the pawls without undue lost motion in this direction. While the slides E^3 are thus positively arrested in their reciprocal movements, the shocks, though comparatively light, are absorbed directly by the slides themselves, the pawls E^1 , E^2 riding smoothly and evenly upon the slides as they are moved the required distance into and out of the magazine.

When a slide E^3 (see Fig. 2) occupies its forward or normal position, the front pawl E^1 is held raised and with its upper end engaged with the leading matrix of the column, while the rear pawl E^2 is held depressed and with its upper end flush or slightly below the bottom of the magazine channel or out of the path of the matrices. At such times, the cam surface e^2 of the slide E^3 is located in front of the rounded lower wall of the recess e of the front pawl E^1 and the cam surface e^3 in similar relation to the upper wall of the recess e of the rear pawl E^2 . Consequently, as the slide is pushed rearwardly against the tension of the spring E^4 by the operation of the key-controlled lever D^2 , the front pawl E^1 will be depressed by the cam surface e^2 and the upper end thereof withdrawn from the magazine and out of engagement with the leading matrix, the rear pawl E^2 at the same time being raised by the cam surface e^1 and its upper end projected into the magazine and into the path of the next or succeeding matrix. In this latter or reverse position of the parts

(see Fig. 3), the cam surface e^1 of the slide E^3 is located immediately rearward of the rounded upper wall of the recess e of the front pawl E^1 and the cam surface e^4 located in corresponding relation to the lower wall of the recess e of the rear pawl E^2 , so that as the pressure on the slide is relieved and the spring E^4 allowed to return the slide to its original position, the cam surface e^1 will project the front pawl E^1 into the magazine and the cam surface e^4 will withdraw the rear pawl E^2 therefrom. The succeeding matrix, which had thus been momentarily detained by the rear pawl E^2 , is then released and promptly intercepted by the front pawl E^1 , which will continue to sustain it until the escapement is again actuated by the finger key.

In the appended claims, the expression "matrices" is intended to embrace male-type or dies as well as female matrices, it being obvious that the invention is as applicable to machines which handle the former elements as to linotype machines proper.

Having thus described my invention, what I claim is:

1. An escapement device for typographical composing machines, comprising a cam slide, a reciprocable matrix-engaging pawl actuated directly thereby, and a fixed guideway in which said pawl is reciprocable.

2. An escapement device for typographical composing machines, comprising a matrix-engaging pawl, a reciprocable slide formed with oppositely disposed cam surfaces for operating the pawl directly, and a fixed guideway in which said pawl is reciprocable.

3. In a typographical composing machine, the combination of a matrix magazine, and an escapement device for controlling the release of the matrices one at a time therefrom, said device comprising a pair of rectilinearly movable pawls adapted to be moved alternately into and out of the path of the matrices, and a reciprocable cam slide for operating the pawls.

4. In a typographical composing machine, the combination of a matrix magazine, and an escapement device for controlling the release of the matrices one at a time therefrom, said device comprising a pair of rectilinearly movable pawls adapted to be moved alternately into and out of the path of the matrices, and a slide formed with oppositely disposed cam surfaces for operating the pawls.

5. In a typographical composing machine, the combination of a matrix magazine, and an escapement device associated therewith, comprising a pair of pawls slidably mounted and movable alternately into and out of the path of the matrices to control their release, one at a time, from the magazine, and a reciprocable cam slide for operating the

pawls, said pawls being mounted and guided at their opposite ends so as to move in a plane perpendicular to that of the magazine, for the purpose described.

6. In a typographical composing machine, the combination of a matrix magazine, a pair of rectilinearly movable pawls adapted to be moved alternately into and out of the path of the matrices for controlling their release, one at a time, from the magazine, a reciprocable cam slide for operating the pawls, a spring for maintaining the slide resiliently in a normal position, and key-controlled devices for actuating the slide against the tension of said spring.

7. In a typographical composing machine, the combination of a matrix magazine, an escapement device associated therewith comprising a pair of pawls formed with open-sided recesses, and a reciprocable cam slide arranged in said recesses and adapted by its reciprocation to move the pawls alternately into and out of the path of the matrices in controlling their release, one at a time, from the magazine.

8. In a typographical composing machine, the combination of a matrix magazine formed with a series of channels wherein the matrices travel on their edges, with a series of escapements, each comprising a pair of independently supported pawls, and a reciprocable cam slide directly engaging the pawls and adapted by its reciprocation to move the pawls alternately into and out of the path of the matrices in controlling their release from the magazine.

9. In a typographical composing machine, the combination of a matrix magazine formed with a series of channels wherein the matrices travel on their edges, with a series of escapements, each comprising a pair of pawls, a reciprocable cam slide engaging the pawls and adapted by its reciprocation to move the pawls alternately into and out of the path of the matrices, and a compression spring for maintaining the cam slide resiliently in its normal position, the springs for the slides of the various escapements being staggered relatively to each other so as to permit close spacing of adjacent slides.

10. In a typographical composing machine, the combination of a matrix magazine, and a series of escapements associated therewith, each comprising a pair of pawls movable alternately into and out of the path of the matrices, and a reciprocable cam slide for operating the pawls, with a supporting frame wherein the escapements are mounted, and retaining plates common to all of the escapements for holding them in place, said plates being detachably secured to the supporting frame, for the purpose described.

11. In a typographical composing machine, the combination of a matrix magazine, and a series of escapements for controlling the re-

lease of the matrices therefrom, said escapements each comprising a pair of pawls slideable in guideways at their opposite ends, and an actuating cam slide movable at right angles to the pawls and arranged to engage the pawls intermediate their ends.

12. In a typographical composing machine, the combination of a matrix magazine, and a series of escapements for controlling the release of the matrices therefrom, said escapements each comprising a pair of pawls slideable in guideways at their opposite ends, and formed between their ends with open recesses, and an actuating slide movable at right angles to the pawls and formed with oppositely disposed inclined portions engaging in the open recesses of the pawls.

13. A combination as in claim 11, characterized by the fact that the cam slides are formed at their opposite ends with stop shoulders to limit the movement of the slides in opposite directions.

14. A combination as in claim 11, characterized by the fact that the escapements as a whole are mounted in a supporting frame made up in removable sections to facilitate the assemblage and disassemblage of the parts.

15. An escapement mechanism for typographical composing machines, said mechanism embodying a series of escapements each comprising the two sliding matrix-engaging pawls E¹, E² and the actuating cam slide E³, together with the supporting frame F having the detachable bottom plates F², F⁴ and F⁵ and the detachable top retaining plate F³.

In testimony whereof, this specification has been duly signed by:

GEORGE P. KINGSBURY.
